UNITED STATES PATENT OFFICE.

ADOLF L. BJÖRKSTAM AND JAMES M. FERGUSON, OF SEATTLE, WASHINGTON.

AUTOMATICALLY-CONTROLLED BY-PASS.

1,031,514.

Specification of Letters Patent.

Patented July 2, 1912.

Application filed October 30, 1911. Serial No. 657,658.

To all whom it may concern:

Be it known that I, ADOLF L. BJÖRKSTAM and JAMES M. FERGUSON, citizens of the United States, and residents of the city of Seattle, in the county of King and State of Washington, have invented certain new and useful Improvements in Automatically-Controlled By-Passes, of which the following is a specification.

Our invention relates to improvements in automatically controlled by-passes, and comprises the novel parts and combinations of parts which will be hereinafter described and pointed out in the claims.

The object of our invention is to improve such devices in general, and particularly to better control the opening and closing of the by-pass valve and to better secure the operation of a detector meter, and to also make it possible to draw water through this detector meter for certain purposes without opening the by-pass valve.

In the drawings we have shown our invention in the form which is now preferred by us.

Figure 1 is a central longitudinal section taken through the by-pass; Fig. 2 is a top plan view with the cover of the ball-receiving chamber removed; Fig. 3 is a transverse sectional elevation taken through the device at the point of union of the two end sections of the casing.

The main purpose of our invention is to provide means for better control and operation of the by-pass valve and also to insure passage of water through the detective meter in sufficient volume to insure its operating as long as the by-pass valve is open, thus giving a more reliable check upon its use.

Our invention is also designed to more effectively remove the valve closing force when the valve is fully open, thereby producing less throttling effect upon the flow.

The principal demand for a device of this character is in connection with the installation of a fire service of stand pipes in buildings, factories, etc., such services being supplied through other pipes than those which supply the regular daily service, and being of a far greater capacity. In this way it is possible to install a meter in the daily service connection of the size which is best adapted to take care of the normal demands, leaving the unusual and larger

demands caused by fire conditions to be taken care of through the by-pass or emergency connection. As the use of water for extinguishing fires is a public use it is not necessary to meter this.

The casing 1 which contains the by-pass valve and its controlling mechanism, is adapted to be connected with the supply main and the stand pipe. It has a through opening or channel of relatively large capacity, within which is a valve seat 12, normally closed by a valve 2. For convenience in manufacture we have shown the casing as composed of three parts, an end 10 which is connected with the supply main, an end 11 which is connected with the stand pipe or delivery end, and a dome or ball-receiving chamber 5, located over the valve and communicating with the delivery end of the casing.

The casing is provided with two outlets, 14 and 15, located at opposite sides of the valve seat and adapted respectively for connection with the supply and delivery ends of a detector meter 6. The meter 6 is connected between these outlets, and, preferably, valves 60 and 61 are associated therewith, so that the meter may be cut out when desired. The purpose of this meter is mainly to provide a check upon the use of the fire connection for other than fire purposes and to show the amount of such use. In connection with such a detector meter we have provided means to more certainly secure a flow of water therethrough when the emergency valve is open, thus providing a check by which to estimate the amount of water which passes through the by-pass valve. At the entrance of the connection 14 through which this meter is supplied, we prefer to provide a diverting flange 16 which projects slightly within the main channel, thereby catching and diverting the water to insure a sufficient flow to operate the meter, even when the valve 2 is wide open.

The valve 2 is connected with an arm 3 which is pivoted at 32 to the outer or lower end of a trackway 13, which is secured to or forms a part of the casing; this trackway having a slight inclination or down grade toward the pivot 32.

The arm 3 to which the valve is secured has two trackway arms 30 extending outward or over the valve and forming a con-

tinuation of the trackway members 13. At their outer ends these may be provided with upturned curves as 31, to stop or hold against further travel, any weight mounted 5 to roll thereon. Upon these arms 30, which are inclined downwardly away from their pivots, is placed a weight, as the ball 4, which will, when the valve is in closed or normal position, roll toward the outer end 10 of this trackway, thereby holding the valve securely closed. The leverage given the weight by these trackway arms is such that the valve cannot be raised except an unusual demand be made upon the pipes supplied 15 therethrough, which unusual demand will reduce the pressure upon the delivery side sufficiently to produce an unbalanced pressure upon the lower side of the valve to lift it from its seat. When this occurs the ball 20 or weight 4 will be raised, the trackway formed by the arms 30 will have its direction of inclination reversed and the ball will roll to and across the pivot upon the fixed trackway 13, or to the position 40 shown by 25 broken lines in Fig. 1. In this position the valve is relieved of all weight of the ball, except such as is required to retain it upon the inclined trackway 13. When the unusual and emergency demand ceases, the 30 weight of the ball, seeking to roll it down the fixed trackway 13, will push gently upon the then upwardly extended arms 30 and assist the natural weight of the valve to close it. As soon as the valve has closed, the 35 inclination which the arms 30 will then have away from the pivot 32, will cause the ball to roll to the outer end of these arms, in which position its weight is acting through a considerable leverage, to hold the valve securely closed. In consequence of the rolling 40 movement given the ball it acts with relative feebleness to close the valve when it is open and strongly to keep it closed when it is once closed. The valve therefore requires 45 but little effort from the passing water to keep it open, thus producing but little throttling effect upon the water while preventing lifting the valve unless a considerable difference in pressures upon opposite sides of 50 the valve is produced. The valve will thus not be raised unless water is drawn off in volume much greater than would be required for any purpose except for putting out fires. 55 By the use of such a device it is feasible to draw water through the fire supply pipes for certain uses and also have this amount correctly registered. The detector meter will correctly register the water thus used so 60 long as the use is not at such rate as will open the emergency valve. By proper proportioning the meter and its connecting pipes the fire pipes may be employed for such regular needs as are of an intermittent 65 character, such as washing down floors, etc.,

and the amount of water so used be registered. While this practice is possible with our device it is not recommended.

What we claim as our invention is:

1. The combination with a valve casing 70 having a valve seat, a valve hinged to the casing above the valve seat, a trackway secured to and swinging with the valve and extending from the pivot outward over the valve, said trackway, when the valve is in 75 closed position, being inclined downward as it extends away from the valve pivot, a weight mounted to roll upon said trackway, and a receiving holder for said weight in position to receive the weight when it is 80 rolled backward beyond the pivot by the upward swinging of the valve.

2. The combination with a valve seat, a valve therefor pivoted above the valve seat to swing upward and open, a trackway secured to and extending over the valve and, when the valve is in closed position, being inclined downward away from the pivot, a weight mounted to roll upon said trackway, said trackway permitting the weight to roll 85 therefrom at the pivot end when the valve is raised, and means for returning the weight to the trackway when the valve closes.

3. The combination with a valve seat, a pivoted valve adapted to close said valve 95 seat, a trackway pivoted at one end to swing with the valve, a weight mounted to roll upon said trackway, and away from its pivot when the valve is in closed position, and means, independent of said trackway, to 100 return the weight to the trackway when the valve closes.

4. The combination with a by-pass and a valve controlling said by-pass and hinged to be opened by an unusual rush of water, a 105 trackway secured to said valve to extend from its hinge outwardly over the valve and downwardly inclined toward its outer end when the valve is closed, a fixed trackway section forming a continuation of said valve-supported trackway beyond its pivot and downwardly inclined toward said pivot, and a weight supported by and adapted to roll upon said trackway.

5. A meter by-pass comprising a casing 115 having a through channel of relatively large capacity and a valve seat surrounding said channel and provided with connections at each side of said valve seat for the attachment of a meter, a valve normally engaging 120 said valve seat to close its channel, an arm constituting a trackway and connected with the valve to be controlled in position thereby to reverse its angle of inclination by raising of the valve, a weight supported by 125 and adapted to roll upon said trackway arm and a fixed, inclined trackway receiving said weight when the valve is raised and acting to return the weight to the trackway when the valve closes.

6. A meter by-pass comprising a casing having a through channel of relatively large capacity and a valve seat surrounding said channel, said casing having an outlet at each 5 side of the valve seat adapted for the connection of a meter, and a diverting flange associated with the meter supplying outlet, a valve adapted to engage said valve seat and hinged above said seat to open with an 10 unusual increase in the flow of fluid, and a movable weight connected with and moved by said valve as it raises and thereby shifted into position to relieve the valve of its

weight when the valve is raised, and by gravity shifted into position as the valve 15 drops to add its weight to that of the valve to hold the latter seated.

In testimony whereof we have hereunto affixed our signatures at Seattle, Washington, this 23rd day of October, 1911.
